UNITED STATES PATENT OFFICE.

HARRY J. HICK, OF ALLIANCE, OHIO.

FILING APPLIANCE.

1,227,550.

Specification of Letters Patent.

Patented May 22, 1917.

Application filed July 23, 1914. Serial No. 852,600.

To all whom it may concern:

Be it known that I, HARRY J. HICK, a citizen of the United States, residing at Alliance, in the county of Stark and State of Ohio, have invented certain new and useful 5 Improvements in Filing Appliances, of which the following is a specification.

The invention relates to a filing appliance for sales bills and other similar papers, in 10 which a plurality of bill holders are operatively mounted in a fire-proof case comprising a rectangular base section and a similar cover section adapted to be swung on the base section to incase the bill holders 15 when closed, and to form a back for the same when opened.

In the former application, filed June 1, 1914, Serial No. 841,976, a filing appliance of this type or character has been illustrated, described and claimed, in which a 20 series of hinged bill holders and an index frame are pivoted to the rim of the rear end of the cover section of the case; in two subsequent applications, filed respectively June 25 8, 1914, Serial No. 843,602, and June 9, 1914, Serial No. 843,962, filing appliances of this type or character have been illustrated, described and claimed, in which a second series of hinged bill holders are operatively 30 connected with the index frame and provided with guiding means for swinging into and out of the base section of the case when the frame is rotated into reclined or upright position; and in a later application, filed 35 June 12, 1914, Serial No. 844,672, a filing appliance of this type or character has been illustrated, described and claimed, in which a single series of hinged holders have their hinged ends pivoted intermediate the end 40 holders to the rear rim of the cover section of the case, with supporting and guiding means for the free ends of the holders in the base section of the case, and with swinging contracting connections between the hinged 45 end of the lower holder of the series and the cover section of the case.

The object of the present invention is to provide a single or continuous series of hinged bill holders having their hinged ends 50 pivoted intermediate the end holders to the rear rim of the cover section of such a case, with supporting, guiding, elevating and sustaining means in the base section of the case, for carrying the forward end of the bill holders of the entire series upward and forward

into operative position, and for thrusting the hinged end of the lower holder upward, when the cover section is rotated into upright position upon the base section of the case. 60

The object of the invention, thus briefly set forth, is attained by the embodiment thereof, illustrated in the accompanying drawings, forming part hereof, in which—

Figure 1 is a side elevation section of the 65 case showing the cover section closed downward upon the base section thereof;

Fig. 2, a fragmentary plan view of the base section showing the guiding and supporting means in depressed position, as in 70 Fig. 1;

Fig. 3, a side elevation section of the case, showing the cover section swung upward upon the rear end of the base section, with the bill holders carried upward and forward 75 into operative position;

Fig. 4, a similar section showing the bill holders above the pivotal connection with the rim of the cover section of the case, rotated into upright position therein; 80

Fig. 5, a side elevation of the case, partly in section, showing all the holders of the series rotated into upright position;

Fig. 6, a fragmentary plan view of the base section of the case, showing the supporting and guiding means in elevated position as in Fig. 5; 85

Fig. 7, a front elevation section on line 7—7, Fig. 5;

Fig. 8, a side elevation section of the case 90 as in Fig. 1, showing a modified arrangement of the springs for elevating and sustaining the supporting and guiding means; and

Fig. 9, a detached plan view of the modified form of supporting and guiding means as shown in Fig. 8. 95

Similar numerals refer to similar parts throughout the drawings.

The case is composed of the substantially 100 similar rectangular bottom or base section 1 and the top or cover section 2, which are operatively connected together by means of the guiding hinge brackets 3, one bracket being located on each side of the rear end portion of the base section; by means of which the cover section can be swung and shifted upon the base section to aline either the top or rear end of the cover section with the rear end of the base section. 105 110

The series of bill holders 4 and 4' are hinged together at the lower rear ends, and the pivots 5 between two adjoining intermediate holders 4^a and 4^b are mounted in 5 the bearing 6 secured on the rear end rim of the cover section; so that the upper rear holders 4 of the series may be referred to as the upper division thereof, and the lower forward holders 4' of the series may be referred to as the lower division thereof.

10 The lower forward bill holder 4^a of the series is pivoted at 7 to the rear end of the frame 8, which may carry an index, not shown, for the bill holders, or may form a 15 table for writing or other use, or may be considered merely as a tray for supporting the superposed bill holders at certain times. Rollers 9 are journaled on each side of the forward end of the frame 8, and tracks 20 composed of the jointed sections 10, 10^a and 10^b are provided on each inner side of the side walls of the base section of the case; upon which tracks the rollers are adapted 25 to rest when the frame 8 is carried downward and rearward into the base section by its rear end pivotal connection with the series of holders, when the cover section is closed downward upon the base section, as shown in Fig. 1.

30 In this relation of the parts, the bill holders are all superposed upon the frame 8, the rear ends of the holders and the frame being supported by and pendent from the intermediate hinge pivot 5 journaled in the bearing 6 secured to the rear rim of the cover section, and the forward ends of the holders and frame being supported by the rollers 9 resting on the lower rear ends of the track sections 10 which are connected at 35 their forward ends by the pivots 11 to the side walls of the base section of the case, all as shown in said Fig. 1.

40 Each track section 10 is preferably made of three laminations or plates, the middle one of which extends downward in the form of the triangular pendent plate 12. The lower angles of triangular plates are connected by the transverse cross bar 13, while the forward portions of the laminated track 45 sections 10 are connected by the transverse abutment bar 14 having its ends pivoted in the track sections; thus forming a swinging frame adapted to oscillate upward and downward upon the pivots 11 at the forward ends of the track sections.

50 Transverse rock bars 15 are provided in the forward end of the base section of the case, which bars have their ends pivoted in the bearing brackets 16 secured to the 55 forward wall of the base section, at a substantial distance below the axes of the track pivots 11; and have a plurality of spring rods 17 secured thereto.

55 The spring rods 17 extend rearward through guiding apertures 18 in the abut-

ment bar, and the coiled compression springs 19 are mounted around these rods between the transverse rock bars and the abutment bar; the energy of which springs acts to thrust the rearward end of the track sections 10 upward.

60 Each track section 10^a is also preferably made of three laminations or plates, the middle plate 20 of which extends forward beyond the ends of the side plates and between the rear end portions of the side plates of the track section 10, to the ends of which it is jointed by means of the pivots 21. Each track plate 20 also extends a short distance forward beyond the pivots 21 and 65 has its forward end notched at 22 to abut the stop pin 23 in the track section 10, when the track sections 10 and 10^a are swung upward into alinement, as shown in Figs. 3, 4 and 5; the rear ends of the triangular plates 12 being cut away to accommodate the forward extension of the middle plates 20.

70 The track sections 10^b are preferably made of single thick plates, the forward ends of which have their sides cut away to form 75 the tenons 24 which extend between the rear ends of the side plates of the track sections 10^a to which they are jointed by means of the pivot 25; the rear ends of the middle plates 20 of the track sections 10^a being shortened for this purpose. The rear ends of the track sections 10^b rest and slide 80 upon the bottom of the base section of the case in the operation of the tracks.

75 One or more sets of rollers 26 and 26^a are 85 journaled on the sides of the frame 8 at or near the rear end thereof, which rollers are adapted to travel upon the several track sections when the same are thrust upward by the springs 19 into the positions shown 90 in Figs. 4 and 5 of the drawings, during 95 the operation of the appliance.

100 In the modified arrangement of the device shown in Figs. 8 and 9, the compression coil springs 19^a are located upon series of 105 overlapping rods 17^a between the cross heads 14^a secured to the overlapping ends of the rods and having apertures 18^a therein for 110 receiving and guiding the overlapping portions of the rods; the other ends of which rods are pivotally secured, respectively, to the cross bar 13 extending between the pendent plates 12 of the track sections 10, and to the brackets 16^a secured to the bottom at 115 the rear end of the base section of the case, as illustrated in Figs. 8 and 9.

120 It is evident that the action of the compression springs 19^a will serve to thrust the rear ends of the track sections upward substantially the same as the action of the compression springs 19, excepting that the modified arrangement permits the use of compression springs of considerably greater length.

125 In the use of the appliance, when the 130

cover section of the case is rotated into upright position and its rear end rim is shifted forward upon the base section, it is evident that the holders 4 and the underlying frame 8 will be carried bodily forward, and the track sections 10 will be so sustained and elevated by the compression springs 19 or 19^a, that the rollers 9, riding thereon, will carry the forward end of the frame and superposed holders upward and forward, and finally over and upon the forward rim of the base section, into the operative position shown in Figs. 3 and 4; in which position the forward ends of all the holders are located above the rim of the base section of the case, and are therefore accessible for the operation of the holders, either singly or collectively, on their hinged rear ends.

20 The parts are so proportioned and arranged that during this operation, the compression springs 19 or 19^a will thrust the track sections upward to bring sections 10 and 10^a into an inclined alinement, with section 10^b inclined downward therefrom, so that the rollers 26 and 26^a at the rear end of the frame 8 may ride upon these track sections, as shown in Figs. 3 and 4.

25 In this relation of the parts, it is evident that the holders 4, 4^a and 4^b, comprising the upper division of the series, may be rotated upon their hinged ends into upright position, either singly or collectively; in which upright position the upper rear 30 holder 4^b of this division is sustained and guided by the abutment rollers 27 provided one in each side of the cover section, and the forward holder 4^a, thereof, is supported by the pivotal bearing 6 on the rear rim 35 of the cover section, as shown in Fig. 4; so that the rotated holders of this division 40 will be maintained in upright position by the action of gravity in the manner well known in this art.

45 And furthermore, when one or more of the bill holders 4', 4'^a and 4'^b, comprising the lower division of the series, are rotated on their hinged ends into upright position, the action of the compression springs 19 or 50 19^a will thrust the track sections upward to bring alined sections 10 and 10^a toward or into horizontal position, with section 10^b inclined downward and rearward therefrom, as shown in Fig. 5; and the energy 55 of the compression springs further serves to sustain in upright position, the holders of the second division which have been rotated into such position, as shown for all these holders in said Fig. 5; in which operation of the parts it is also evident that the swinging movement of the rear end of the frame 8 will cause the forward end thereof to slide forward and rearward upon the forward rim of the base section of the 60 case, while the rollers 26 and 26^a on the

rear end of the frame will ride upon the yieldingly sustained track sections 10 and 10^a.

For closing the case, it is preferred to rotate all the holders of the series forward 70 upon their hinged ends into reclined position superposed upon the frame 8, as shown in Fig. 3, whereupon a forward swinging and rearward shifting of the cover section to close it upon the base section of the case 75 will carry the frame 8 and superposed holders thereon bodily downward and rearward within the two sections of the case, as shown in Figs. 1 and 8; during which movement the frame rollers will ride downward upon the track sections in a reverse manner to that described for the upward forward movement, while the track sections are depressed against the yielding action of the compression springs, into the 80 85 position shown in Fig. 1.

It will be understood that the use of a distinctive frame, illustrated herein as an index frame, on the lower end of the series of bill holders is not an essential feature 90 of the broader invention, for it is evident that the functions of such a frame can be performed by the lower bill holder of the series; but the use of such an index frame is preferred, as a matter of convenience, 95 construction and operation.

I claim:

1. A filing case including similar base and cover sections with guiding hinge connections for swinging and shifting the cover section upon the base section, a plurality of hinged holders mounted in the case having their hinged ends depending from a pivotal connection with the rear end of the cover section, and means for supporting and guiding the free ends of the holders upward and forward from within the base section over the forward rim thereof including spring supported tracks having their forward ends pivoted to the base section and their rear ends adapted to rest upon the bottom thereof.

2. A filing case including similar base and cover sections with guiding hinge connections for swinging and shifting the cover section upon the base section, a plurality of hinged holders mounted in the case having their hinged ends depending from a pivotal connection with the rear end of the cover section, and means for supporting and guiding the free ends of the holders upward and forward from within the base section over the forward rim thereof including spring supported jointed tracks having their forward ends pivoted to the base section and their rear ends adapted to rest upon the bottom thereof.

3. A filing case including similar base and cover sections with guiding hinge connections for swinging and shifting the cover

- hinged holders mounted in the case having their hinged ends depending from a pivotal connection with the rear end of the cover section, a frame having its rear end pivoted 5 to the rear end of the lower holder, means for supporting and guiding the free end of the frame upward and forward from within the base section over the forward rim thereof including tracks having their forward 10 ends pivoted to the base section, and springs bearing upon the base section for thrusting the tracks upward to elevate and sustain the hinged end of the frame.
12. A filing case including similar base and cover sections with guiding hinge connections for swinging and shifting the cover section upon the base section, a plurality of hinged holders mounted in the case having their hinged ends depending from a pivotal 15 connection with the rear end of the cover section, a frame having its rear end pivoted to the rear end of the lower holder, means for supporting and guiding the free end of the frame upward and forward from within the base section over the forward rim thereof including tracks having their forward 20 ends pivoted to the base section, means for thrusting the tracks upward to elevate and sustain the hinged end of the frame, and rollers on the hinged end of the frame for traveling on the tracks when elevated.
13. A filing case including similar base and cover sections with guiding hinge connections for swinging and shifting the cover section upon the base section, a plurality of hinge holders mounted in the case having their hinged ends depending from a pivotal 25 connection with the rear end of the cover section, means for supporting and guiding the free ends of the holders upward and forward from within the base section over the forward rim thereof including tracks having their forward 30 ends pivoted to the base section, means for thrusting the tracks upward to elevate and sustain the hinged end of the frame.
14. A filing case including similar base and cover sections with guiding hinge connections for swinging and shifting the cover section upon the base section, a plurality of hinge holders mounted in the case having their hinged ends depending from a pivotal 35 connection with the rear end of the cover section, means for supporting and guiding the free ends of the holders upward and forward from within the base section over the forward rim thereof including tracks having their forward 40 ends pivoted to the base section, means for thrusting the tracks upward to elevate and sustain the hinged end of the frame, and rollers on the hinged end of the frame for traveling on the tracks when elevated.
15. A filing case including similar base and cover sections with guiding hinge connections for swinging and shifting the cover section upon the base section, a plurality of hinged holders mounted in the case having their hinged ends depending from a pivotal 45 connection with the rear end of the cover section, means for supporting and guiding the free ends of the holders upward and forward from within the base section over the forward rim thereof including tracks having their forward 50 ends pivoted to the base section, means for thrusting the tracks upward to elevate and sustain the hinged end of the frame, and rollers connected with the hinged end of the lower holder adapted to travel upon the tracks when elevated.
16. A filing case including similar base and cover sections with guiding hinge connections for swinging and shifting the cover section upon the base section, a plurality of hinged holders mounted in the case having their hinged ends depending from a pivotal 55 connection with the rear end of the cover section, with means for supporting and guiding the free ends of the holders upward and forward from within the base section over the forward rim thereof, and means bearing in the base section for elevating and sustaining the hinged ends of the holders.

HARRY J. HICK.
